OIL BURNER POT SUPPORTING MEANS
FOR HEATERS

Henry Weyenberg and Walter R. Kimberley, Holland, Mich., assignors to Holland Furnace Company, Holland, Mich., a corporation of Delaware

Application November 30, 1945, Serial No. 631,860

7 Claims. (Cl. 126—94)

1

This invention relates to a water heater and more particularly to a water heater in which oil is used as the fuel.

It is the general object of the invention to provide a new and improved hot water heater.

Among the objects of the present invention are: to provide a novel and improved heater of the character referred to; to provide a novel arrangement of oil burner and associated parts for heaters for heating water and the like; to provide a novel mounting for the oil burning pot; and the provision of a novel combination of an air inlet opening and plunger rod assembly.

Other objects and advantages will become readily apparent from the following detailed description taken in connection with the accompanying drawings, in which:

Fig. 1 is a vertical longitudinal central section through a heater embodying our invention, parts being shown in side elevation for clearness.

Fig. 2 is a top plan view of Fig. 1.

Fig. 3 is a fragmentary vertical central section through the lower portion of our heater and showing the structure for mounting the oil burner pot therein.

Fig. 4 is a transverse section on the line 4—4 of Fig. 3.

Our invention further resides in the combination, construction and arrangement of parts illustrated in the accompanying drawings, and while we have shown therein a preferred embodiment we wish it understood that the same is susceptible of modification and change without departing from the spirit and scope of the appended claims.

Referring more in detail to the drawings our improved heater comprises a metal outer casing 1 mounted at the bottom upon a base 2 having legs 3, and having fixed to the top thereof a top plate 4. Spaced inwardly a distance from the outer casing 1 is an inner metal casing 5 which is likewise mounted upon base 2 and at its upper end is provided with the top plate 6 likewise spaced from the outside top plate 4. The space between the outer and inner casings 1 and 5, and between the top plates 4 and 6 is filled with any suitable insulating material 7 as desired. Extending through registering openings in the top plates 4 and 6 and the adjacent portions of the insulating material 7 is a tube 8 through which passes the gaseous products of combustion from the oil burner pot later more fully described. Any suitable means (not shown) may be applied at the top of tube 8 for conducting the gases of combustion from the tube 8 to a flue leading to

2

the outside. Threadably passing through registering openings in the top portions 4 and 6, one on each side of the tube 8, are nipples or the like 9 and 10. Connected with nipple 9 and extending to the lower portion of the inside of the tank is a fill pipe 11 through which the water or other liquid to be heated is introduced into the tank. Through nipple 10 may be passed any suitable pipe or tube to conduct the heated water from the inside of the tank to any desired place of use.

As seen in Figs. 1 and 3 there is provided within the tank a distance above the bottom end thereof a curved bottom plate 12 having a central opening 13 through which extends the bottom end of tube 8, which tube is welded or otherwise secured in watertight relation to bottom plate 12, and which plate may also be welded or otherwise secured in watertight relation to the interior of the inner casing 5. As seen in Fig. 1 the bottom end 14 of tube 8 extends a slight distance below the bottom plate 12. Secured at diametrically opposite points to the lower face of bottom plate 12 are bracket members 15 each provided in its vertical web with an opening 16 through which are hooked the curved ends 17 of the hanger rods 18, which at their bottom ends are formed with threads 19 threaded over which are wing nuts 20, above which wing nuts are washers 21. Support-bar 22 is provided at its opposite ends with openings 23, one of which for convenience in mounting is in the form of an open ended slot, through which openings extend the hanger rods 18 so that the ends of the support-bar, after the parts are assembled, rest upon the washers 21. As will be understood the support-bar 22 is slipped over the rods 18 after which the washers and wing nuts are applied. As seen in Fig. 3 this structure constitutes a hanger or support within which the oil burner pot is mounted.

Support-bar 22 at its middle portion is formed with an upwardly extending rib 24. Positioned directly above support-bar 22 is a plate 25 formed at its mid portion with longitudinally spaced depending ribs 26, within the space between which is fulcrumed the rib 24 of the support-bar. The depth of ribs 26 is less than the height of rib 24 so as to permit a rocking action of the plate 25 as may be required to properly position the parts during assembling. Positioned in spaced relation around the outer portion of the plate 25 are three equally spaced upstanding ribs 28, each of which have a curved recess 29 to fit the bottom corner edge of the burner pot so as to posi-

tion the burner pot with relation to the heat-plate and hold it thereon. The oil burner pot 30, which is formed in its side walls with air holes 31, is provided at its top with a top plate 32 having an annular groove 33 formed therein to be seated against the bottom end edge of the tube 8. Formed centrally in the top plate 32 is an opening 34 having communication on its lower side with the interior of the burner pot and having communication on its upper side with the interior of the tube 8, so that the hot combustion gases may pass from the interior of the pot to the interior of the tube 8. The combustion of these gases will be substantially completed within tube 8 to heat the water or other liquid within the tank.

In assembling the burner pot in position the hanger rods 18 are first inserted by means of their hooks 17 in the brackets 15, which brackets are each welded or otherwise secured by the angular leg 35 to the lower face of the bottom plate 12. The support-bar 22 will then be positioned upon these hanger rods through the medium of openings 23 and the washers 21 applied over these rods below the support-bar. The wing nuts will then be threaded onto the lower end of these hanger rods, the heat-plate placed upon the support-bar with rib 24 in the space between the shorter ribs 26, and the burner pot 30 positioned within the curved recesses 29 of ribs 28. The pot top plate 32 is then placed on the burner pot with the annular flange 36 positioned within the upper edge of the burner pot walls, and the bottom end edge of the tube 8 inserted in groove 33, after which the nuts 20 will be tightened upon the hanger rods 18 to bring these parts into secured and tightened position. It will be understood that as these parts are being clamped together as described, the plate may tilt on the support-bar as may be required to make a tight joint between the bottom of tube 8 and the top plate 32 and bring all of these parts in desired assembled and tightened relationship. As the clamping of these parts proceeds one or the other of the nuts 20 may be advanced faster or slower than the other so as to afford a proper seating of the various parts, any adjustment being provided for by the tilting of the plate as described above.

Extending through the wall of the pot 30 at the bottom thereof and projecting outwardly therefrom is a plunger rod assembly 37 the rod 38 of which extends through the opening 39 in the inspection door 40, there being provided a handle 41 on the outer end of the rod outside of the inspection door 40 so as to enable manipulation of the rod to control entry of oil to the interior of the pot as desired. As noted in Fig. 3 the opening 39 around rod 38 is of substantially greater size than the size of the rod and handle so as to permit the entry of air through hole 39 to the interior of the space 42 in the tank below the tank bottom 12, to aid combustion of the oil within the pot and within the tube 8, such air passing through openings 31 in the pot walls into the interior of the pot. As will be understood a shallow layer of oil will be present in the bottom of the pot so as to provide a large upper surface of oil for vaporization. The pipe-T 43 in the plunger rod assembly will be connected to any suitable source of oil supply which oil will be conducted as desired through the pipe connection 44 to the interior of the pot.

From the above it will be seen that we have provided an improved water heater in which the oil burner pot is mounted in a novel manner

within the heater, the arrangement of parts between the burner pot 30 and the tube 8 being such that maximum heat will be transmitted through the walls of the tube 8 to the water inside of the tank. Also it will be understood that our adjustable arrangement of parts for clamping the oil burner pot in position at the bottom of the combustion tube is such that the plate, due to its tiltable connection with the support-bar will automatically bring these parts into proper position with relation to each other during tightening of the nuts 20. A drain cock 45 is provided near the bottom of the tank to enable draining of the tank as desired. Any well known and suitable heat regulating means may be used as desired for regulating the temperature of the water in the tank.

We claim:

1. Oil burner pot supporting means comprising, an apertured bottom member of a device to be heated, a plurality of burner hangers supported on and extending downwardly from the bottom member, a support bar secured to said hangers, a plate on said support bar, an oil-burning pot positioned between said plate and said bottom member below the aperture in the latter, said plate having spaced upstanding projections upon which the pot rests to form air spaces between said plate and the bottom portion of the pot.

2. Oil burner pot supporting means comprising, an apertured bottom member of a device to be heated, spaced apart angle brackets secured to the bottom member on opposite sides of the aperture therein, elongated hangers each having at its upper end a hook engaging through an opening in one of said brackets, threads on the lower end of each of said hangers, a support bar having openings at its ends through which the hangers pass, a plate tiltably mounted on the support bar in spaced relation thereto, an oil-burning pot mounted on said plate in spaced relation thereto, a top plate on said pot and having an opening communicating with the interior of the pot and said aperture in the bottom member, and threaded tightening means on said hangers for clamping said plate, pot and top plate between the support bar and the bottom member.

3. Oil burner pot supporting means comprising, an apertured bottom member of a device to be heated, a plurality of hangers each supported at its upper end on said bottom member, a support bar adjustably secured to the lower ends of said hangers, a plate tiltably mounted on the support bar, and an oil-burning pot mounted on said plate between the plate and bottom member.

4. Oil burner pot supporting means comprising, an apertured bottom member of a device to be heated, a tubular member extending downwardly a short distance through the aperture of the bottom member, a plurality of hangers each having a connection at its upper end with said bottom member, a support bar having connections at its ends with the lower ends of said hangers, a plate mounted on said support bar, an oil-burning pot mounted on said plate, an apertured top plate on said pot and contacting the bottom end of said tubular member, said first-mentioned plate having the major part of its lower face spaced from the support bar and the major part of its upper face spaced from the bottom of the pot, whereby to provide air spaces between these parts.

5. Oil burner pot supporting means as claimed in claim 4, in which the support bar and first-mentioned plate have central means for tiltably

connecting them relative to each other, said connections between the support bar and hangers being adjustable for tightly clamping the support bar, the first mentioned plate, the pot, said top plate and the bottom end of said tubular member together.

6. Oil burner pot supporting means comprising, a bottom member of a device to be heated, a pair of burner hangers mounted on the bottom member and depending therefrom, a support bar connected to said hangers, a plate mounted on said support bar and having a plurality of spaced upstanding projections, an oil-burning pot mounted on said projections in spaced relation with the plate, said bottom member having a central opening, a tubular member extending downwardly a short distance through said central opening, and means connecting the top of the pot with the bottom end of the tubular member, whereby when the hangers are tightened against the support bar the pot will be clamped between the plate and the tubular member.

7. Oil burner pot supporting means as claimed in claim 6, in which the support bar is tiltably connected to the plate with a substantial air space therebetween.
